US0D1057518S

(12) **United States Design Patent** (10) **Patent No.:** **US D1,057,518 S**
(45) **Date of Patent:** **** Jan. 14, 2025**

(54) **BOTTLE WITH STRAW LID**

(71) Applicant: **Yu He**, Yangjiang (CN)

(72) Inventor: **Jieying He**, Guangzhou (CN)

(73) Assignee: **Yu He**, Yangjiang (CN)

(**) Term: **15 Years**

(21) Appl. No.: **29/835,396**

(22) Filed: **Apr. 19, 2022**

(51) LOC (15) Cl. **07-01**

(52) U.S. Cl.

USPC **D7/510**

(58) **Field of Classification Search**

USPC D3/202; D7/300, 300.1, 300.2, 312, 314, D7/316, 318, 319, 320, 321, 322, 392, D7/392.1, 396.1, 396.2, 507, 509, 510, D7/511, 513, 523, 532, 533, 535, 536, D7/548, 608, 619.1, 622, 635, 900; D9/436, 440, 447, 500, 516, 531, 549, D9/716

(57) **CLAIM**

The ornamental design for a bottle with straw lid, as shown and described.

DESCRIPTION

FIG. 1 is a front perspective view of a bottle with straw lid, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the bottle with straw lid that forms no part of the claimed design.

1 Claim, 7 Drawing Sheets
